UNITED STATES PATENT OFFICE.

JOHN QUINCY BROWN, OF OAKLAND, CALIFORNIA.

TROLLEY.

SPECIFICATION forming part of Letters Patent No. 764,224, dated July 5, 1904.

Application filed April 12, 1904. Serial No. 202,800. (No model.)

To all whom it may concern:

Be it known that I, JOHN QUINCY BROWN, a citizen of the United States, residing at Oakland, in the county of Alameda and State of California, have invented new and useful Improvements in Trolleys, of which the following is a specification.

My invention relates to improvements in overhead current-collecting devices for trolley-cars, and particularly for high-speed heavy multiple-unit electric trains for interurban service. A trolley suitable for such use must be capable of taking a heavy current and of operating at high speeds on curves as well as on a straight track and be strong enough to withstand the tremendous lateral strain under such circumstances, and where the trains run in subways it must accommodate itself to the often low head-room and must be capable of passing under crossings with regular trolley-wires while the train is at full speed. Besides satisfying these conditions my invention has for its object the construction of a trolley that will not leave the overhead conductor in any direction nor while the train is running at any speed; that will permit the train to be run in either direction without reversal of the trolley; that will be durable and will reduce the wear on the trolley-line and simplify and cheapen overhead construction, present trolley-wheel methods requiring an expensive arrangement of overhead frogs, &c.; that will permit rapid switching, and which will be practically noiseless in operation.

The invention consists of the parts and the construction and combination of parts, as hereinafter more fully described and claimed, in which—

Figure 1 is a side elevation of my device. Fig. 2 is an end view of same. Fig. 3 is one end of the trolley-roller, shown in section with guard-support. Fig. 4 is an end view of Fig. 3. Fig. 5 is a front view showing clamping means for roller-axle. Figs. 6 and 7 show upper and lower frame-bearings as would appear with frame in alinement.

Where cars are to be operated in multiple-unit trains, it is impracticable to employ the ordinary trolley pole and wheel by reason of the liability of the wheel leaving the wire and

damaging both the overhead gear and the trolley-pole.

My trolley comprises a jointed double diamond-frame lazy-tongs structure composed of four rectangular frames A A' B B', preferably of angle-iron and suitably braced and hinged together and operating so that the contact member or trolley-roller 2, which is supported between the upper edges of the two topmost frames B B', may rise and lower to accommodate itself to the varying heights of the trolley-wire. The two lower frames A A' are separately pivoted at their lower ends on individual shafts 3, mounted in a fixed support, and these frames have interengaging segmental gears 4, whereby each will partake of precisely the same pivotal movement. Where the respective pairs of frames A B and A' B' are hinged together, they are provided with long bearings to support them laterally. In the present instance I have shown the lower ends of the upper frames B B' as carrying relatively long axially-aligned sleeves 5 and the upper ends of the lower frames A A' as carrying the perforated offset journal parts 6, which are adapted to fit over the outer ends of the sleeves 5. A pivot-rod 7 is adapted to be slipped through each set of sleeves and journal parts 6 and to be held in place by suitable means, as the nuts 8. The upper and lower frames are thus free to pivot on the rods 7, the sleeves 5 affording a sufficiently long bearing to give rigidity to the structure and enable it to withstand the severe strains it is subjected to, particularly when the train is rounding curves at high speed. A single-frame structure of this character is absolutely impracticable, as it would lack necessary strength. This entire device is designed toward overcoming the inherent structural defects of other trolleys of this class.

The upper ends of the topmost frames B B' terminate in interengaging segmental gears 9, which turn on individual pivots 10. The inner ends of the latter are fastened in the castings 11, which support the ends of the non-rotatable axle 12 of the trolley-roller 2. The outer ends of the pivots 10 are secured in castings 13. The upper portions of the castings 11 and 13 have downwardly and out-

wardly inclined projections 14, disposed each in the same plane, to which the lateral inclined curved guards or pick-ups 15 are made fast. When the guards have been bolted to the inclined projections 14, the castings are united into a rigid structure and give proper support and bearing for the gears 9. These gears are essential for the maintenance always of the vertical position of the guards. The roller-
10 axle 12 is clamped in the castings 11 by means of the blocks 16 and nuts 17, screwing onto studs in the castings.

The trolley-roller is especially designed to withstand excessive wear either of itself or the 15 trolley-wire, to avoid heating at the bearings, and to be as noiseless as possible. It consists of an outer tubing of brass or other suitable conducting material secured at each end to an interior hub portion 18, provided with suitable graphite bushings 19, which run on the stationary axle 12. The hubs are provided with annular oil channels or pockets 20, which may be filled from time to time through an opening 21 at each end of the roller and normally closed by means of a machine-screw set 25 into the periphery of the roller. 22 is a cylindrical partition or roll of fiber or like non-resonant matter extending between the hub portions 18 and out of contact with the axle. 30 23 represents fiber disks, and the space between the roll and disks and outer brass tubing is packed with waste, as shown at 23'. This construction very effectually deadens all noise, while the wear on the bearing parts is 35 reduced to a minimum.

In case a roller or roller-axle is to be taken out and replaced it can be quickly done by loosening and removing the clamps 16.

To hold the contact-roller to the trolley-wire, a series of strong tension-springs 24 are arranged with one end secured near the bottom of one of the lower frames, as A', and the other secured to brackets 25 near the top of the other lower frame, so that the springs 40 will always lie in a plane approximately or 45 nearly parallel with the latter frame. This way of attaching the springs has been found quite important, as it gives practically an even tension on the trolley-wire at all ordinary working heights, since by attaching the 50 lower ends of the springs close to the pivot of the two lower frames the arc described by those lower spring ends is subject to very little variation, whereas to run the springs 55 horizontally would cause them to be continually opening and closing through quite a wide range, while the up-and-down movement of the roller might be comparatively slight. The tension of the springs may be adjusted 60 by an eyebolt 26.

The contact between the roller and the metal conducting trolley-frame is effected by the usual frictional contacts 27.

28 is a block for the purpose of causing the 65 springs 24 to exert a tension in a direction

such as to straighten the trolley-frame after it has been abnormally depressed.

The lateral guides or guards 15 are inclined outwardly and downwardly, and their upper surfaces are substantially continuous with the top edge of the trolley-roller, so that the trolley-wire may easily pass off over the ends of the roller or run up the guards onto the rollers, as where the train passes from a single track to double track, or vice versa. 75 Without these guides or guards it would be impossible for the roller to pass, for instance, from a branch to a main-line trolley-wire, without jamming in the fork of the wire and tearing things to pieces. The guards act as 80 pick-ups for the lower wire and lead it gradually and automatically onto the roller. The guards are essential to the operativeness of the rest of the device.

Among the points to be particularly noted 85 in the present structure are the double frame, its means for bracing against lateral strain, the means for supporting the trolley-roller and for supporting the trolley-guards, the specific roller construction, the particular 90 form of guards, and the spring-tension devices for the frame.

Having thus described my invention, what I claim, and desire to secure by Letters Patent, is—

95

1. A trolley comprising a double diamond-shape spring-actuated structure made up of a series of conjoined upper and lower rectangular frames each of substantially uniform width transversely whereby the sides of the lower frames are disposed vertically in line with the sides of the upper frame, and a long trolley-roller supported between the ends of the opposite side bars of the uppermost frame. 100

2. A trolley for multiple-unit trains comprising a double diamond-shape spring-actuated structure made up of a series of conjoined rectangular frames, each comprising parallel side bars spaced uniformly from each other and with the upper frame substantially in line 105 with the corresponding side bars of the lower frame, a trolley-roller supported on a stationary axle between the ends of the uppermost of said frames and lateral downwardly-curved guards carried by the structure and having 110 their upper surfaces substantially continuous with the top edge of the roller.

3. A trolley for multiple-unit trains comprising a double diamond-shape spring-actuated structure made up of a series of conjoined 115 rectangular frames, each comprising parallel side bars spaced uniformly from each other and with the upper frame substantially in line with the corresponding side bars of the lower frame, a trolley-roller supported on a stationary axle between the ends of the uppermost of said frames and lateral downwardly-curved guards carried by the structure and having 120 their upper surfaces substantially continuous with the top edge of the roller, said guards 125

130

disposed in approximately a vertical plane and means for maintaining the guards in such plane.

4. A trolley for multiple-unit trains comprising a double diamond - shape structure made up of four pivotally-connected rectangular frames, two of said frames being above and two below the horizontal central line of the structure and said frames so disposed that 10 the sides of each are parallel and the sides of the upper frames are substantially in line with the corresponding sides of the lower frames, a shaft secured adjacent to the upper end of the structure, and a trolley-roller rotatable on 15 said shaft, means for pressing the roller normally against the trolley-wire and curved lateral trolley-guards having their upper surfaces substantially continuous with the top edge of the roller.

20 5. A trolley for multiple-unit trains comprising a double diamond - shape structure made up of four pivotally-connected rectangular frames, a shaft secured adjacent to the upper end of the structure, and a trolley-roller 25 rotatable on said shaft, means for pressing the roller normally against the trolley-wire and curved lateral trolley-guards having their upper surfaces substantially continuous with the top edge of the roller, said trolley-guards 30 lying substantially in a vertical plane and means for maintaining them in such position.

35 6. A trolley for multiple-unit trains, comprising a diamond - shape, jointed spring-actuated frame, a rotatable collector carried by said frame, and downwardly-curved laterally-projecting guards disposed in approximately a vertical plane and having their upper surfaces substantially continuous with the trolley-wire-supporting surface of the collector, 40 and means for maintaining the guards in vertical position irrespective of the elevation of the collector.

45 7. A trolley comprising a series of conjoined upper and lower frames, intermeshing gears carried by the upper frames and similar gears carried by the lower frames, a trolley-roller supported by the upper frames, lateral downwardly-inclined guards and means for pressing the roller normally against the 50 trolley-wire.

55 8. A trolley comprising a series of conjoined upper and lower frames, intermeshing gears carried by the upper frames and similar gears carried by the lower frames, a trolley-roller supported by the upper frames, lateral downwardly-inclined guards and means for pressing the roller normally against the trolley-wire, said means including tension-springs secured at one end to one of said 60 lower frames adjacent to its pivotal connection with the other lower frame, and the other end of said springs secured to a bracket or like support on the other of said lower frames whereby the springs are maintained approximately parallel to the last-mentioned frame. 65

9. A trolley comprising a series of conjoined upper and lower frames, intermeshing gears carried by the upper frames and similar gears carried by the lower frames, a trolley-roller supported by the upper frames, 70 lateral downwardly-inclined guards and means for pressing the roller normally against the trolley-wire, said means including tension-springs secured at one end to one of said lower frames adjacent to its pivotal connection with the other lower frame, the other end of said springs secured to a bracket or like support on the other of said lower frames whereby the springs are maintained approximately parallel to the last-mentioned frame, 75 and means to cause said springs always to exert a tension to lift the roller. 80

10. A trolley comprising a series of conjoined upper and lower frames, the upper frames interconnected and arranged to support a trolley-roller intermediate of them, a trolley - roller, the lower frames interconnected, and tension-springs having one end attached near the lower end of one of said lower frames and near the top of the other 90 lower frame.

11. A trolley comprising a series of conjoined upper and lower frames, the upper frames interconnected and arranged to support a trolley-roller intermediate of them, a 95 trolley - roller, the lower frames interconnected, tension - springs having one end attached near the lower end of one of said lower frames and the other end near the top of the other lower frame, and a stop interposed in 100 the path of the springs to cause said springs to exert an upward tension when in their more nearly horizontal position.

12. A trolley comprising a series of conjoined upper and lower sets of frames, one of said sets having axially-alined elongated bearing portions embracing pivot-rods common to the other set of frames and serving to support the trolley against lateral strain, a trolley-roller supported by the upper frames and 105 means for forcing said roller normally upward.

13. A trolley comprising a series of conjoined upper and lower sets of spring-actuated rectangular frames, said lower frames connected together whereby each partakes of the same pivotal movement, said upper frames similarly connected, a trolley-roller, one of said sets of frames having axially - alined sleeves embracing pivot-rods common to the 110 other set of said frames, said sleeves serving as elongated bearings to support the trolley against lateral strain.

14. A trolley comprising a series of conjoined upper and lower sets of spring-actuated 115 rectangular frames, said lower frames connected together whereby each partakes of the same pivotal movement, said upper frames similarly connected, a trolley-roller, one of said sets of frames having axially - alined 120

130

- 5 sleeves embracing pivot-rods common to the other set of said frames, said sleeves serving as elongated bearings to support the trolley against lateral strain, and lateral inclined guards carried by said frames and arranged to direct the trolley-wire on and off the rollers.
- 10 15. A trolley comprising a series of conjoined upper and lower sets of spring-actuated rectangular frames, said lower frames connected together whereby each partakes of the same pivotal movement, said upper frames similarly connected, a trolley-roller, one of said sets of frames having axially aligned sleeves embracing pivot-rods common to the other set of said frames, said sleeves serving as elongated bearings to support the trolley against lateral strain, lateral inclined guards carried by said frames and arranged to direct the trolley-wire on and off the rollers, said 20 guards disposed in substantially in a vertical plane and means for maintaining them in such plane.
- 15 25. A trolley comprising a series of conjoined upper and lower spring-actuated frames, castings pivoted to and connecting the upper frames, a trolley-roller supported by said castings and lateral inclined trolley guides or guards carried by said castings.
- 30 35. 17. In a diamond-frame trolley, castings connecting the upper arms thereof, means whereby said arms partake of the same relative movement to maintain the castings horizontal and trolley guides or guards carried by said castings.
- 40 45. 18. In a diamond-frame trolley, castings connecting the upper arms thereof, means whereby said arms partake of the same relative movement to maintain the castings horizontal, trolley guides or guards carried by said castings, a shaft supported by said castings and a trolley-roller turnable on said shaft.
- 45 19. In a diamond-frame trolley, castings connecting the upper arms thereof, means whereby said arms partake of the same relative movement to maintain the castings hori-

zontal, trolley guides or guards carried by said castings, a shaft supported by said castings and a trolley-roller turnable on said shaft, the upper surface of said roller and guards being substantially continuous.

50

20. In a diamond trolley, means for causing the upper arms thereof to partake of the same pivotal movement, a trolley-axle support on said arms, said support including castings pivoted to and connecting the said arms, a trolley-axle fixed in the castings, and a trolley-roller turnable on said axle.

55

21. In a diamond trolley, means for causing the upper arms thereof to partake of the same pivotal movement, a trolley-axle support on said arms, a trolley-axle, a trolley-roller turnable on said axle, and lateral inclined guards carried by said trolley-axle support.

60

22. A trolley-roller having a central stationary axle, and a filling of waste or like non-resonant matter surrounding said axle.

65

23. A trolley-roller having a central stationary axle, and a filling of waste or like non-resonant matter surrounding and out of contact with said axle.

70

24. A trolley-roller composed of a hollow metal conducting-cylinder, an inner concentric fiber cylinder, a non-resonant packing between said cylinders, and hub portions supporting said outer cylinder.

75

25. The combination with a non-rotatable axle, of a metal cylinder concentric and supported out of contact therewith and turnable thereabout, a cylindrical fiber partition intermediate of the metal cylinder and axle and a waste or like non-resonant packing intermediate of said partition and cylinder.

80

In testimony whereof I have hereunto set my hand in presence of two subscribing witnesses.

JOHN QUINCY BROWN.
